(57) **CLAIM**

The ornamental design for a tackle bag, as shown and described herein.

DESCRIPTION

FIG. 1 is a front left perspective view of a tackle bag with a lid closed

FIG. 2 is a rear left perspective view of the tackle bag with the lid closed;

FIG. 3 is a top view of the tackle bag and the lid;

FIG. 4 is a bottom view of the tackle bag;

FIG. 5 is a front view of the tackle bag with the lid closed;

FIG. 6 is a rear view of the tackle bag with the lid closed;

FIG. 7 is a left side view of the tackle bag with the lid open;

FIG. 8 is a right side view of the tackle bag with the lid open;

FIG. 9 is a front left perspective view of the tackle bag with the lid open; and,

FIG. 10 is a front right perspective view of the tackle bag with the lid open.

The various components in broken lines show portions of the tackle bag that form no part of the claimed design.

1 Claim, 10 Drawing Sheets
